SOLVENT COMPOSITION

Hugh G. Webster, Detroit, Mich., assignor, by
mesne assignments, to Kolene Corporation, De-
troit, Mich., a corporation of Michigan

No Drawing. Application December 29, 1938,
Serial No. 248,191

6 Claims. (Cl. 252—172)

This invention relates to solvents for use in dry cleaning, metal cleaning and allied uses, one of which is to destroy the bond of rubber partially or wholly vulcanized to fabric or metal and other 5 similar uses in the rubber industry, and has for its object to provide a solvent comprising a mixture of inflammable and non-inflammable liquids characterized by low toxic qualities, entire lack of flash point and inflammability, excellent cleaning properties and economy of manufacture or mix. This application is a continuation in part 10 of my application Serial No. 235,813 filed October 19, 1938.

It has been proposed to mix a non-inflammable 15 chlorinated hydrocarbon such as carbon tetrachloride with an inflammable hydrocarbon such as naphtha or gasoline in order to obtain a price advantage over the chlorinated hydrocarbons, however, the result has usually been a mixture 20 which is highly toxic, corrosive to metals and inflammable for the reason that the chlorinated hydrocarbons have, to all intents and purposes, a single boiling point, whereas the inflammable hydrocarbons having a boiling range of fifty degrees or over so that the two will separate during 25 distillation. The principal object of this invention is to provide a solvent composed of a mixture of non-inflammable chlorinated hydrocarbons and inflammable hydrocarbons which will 30 not separate during distillation. The principal object of this invention is to provide a solvent composed of a mixture of non-inflammable chlorinated hydrocarbons and inflammable hydrocarbons which will not separate during distillation and 35 which will overcome the other mentioned previous disadvantages. More particularly, it is the object to provide a mixture of non-inflammable chlorinated hydrocarbons of the order of carbon tetrachloride, trichlorethylene, perchlorethylene 40 or the like and an inflammable of the order of motor benzol and to inseparably bind them together. By so doing I have found that the mixture will not corrode iron, steel or aluminum, its toxic qualities are materially reduced, it has dry 45 cleaning qualities and requires less spotting, and it can be produced at a substantial price advantage over any of the chlorinated hydrocarbons alone.

Another object is to provide a liquid which acts 50 as a detergent in removing rubber from various fabrics or metal. When fabric to which rubber clings during pre-heating for or during vulcanization processes is immersed in this solvent for a period as short as six minutes the rubber loses its 55 adhesive qualities and is easily removed from the

fabric or metal as by scraping or brushing or agitation. Solvents such as carbon tetrachloride alone drive the rubber into the fabric rather than removing it.

More particularly it is an object to provide a 5 mixture of a non-inflammable liquid having a substantially constant cooling point with a hydrocarbon cut, preferably unsaturated and having a relatively wide boiling range, to bind these together by the addition of a higher boiling non-inflammable which has the function of dissolving the two lower boiling members thereby causing them to boil in the same temperature range without separation even though the distillation is carried on very slowly. Motor benzol is preferred 10 as the inflammable constituent because it contains, in small quantities, higher boiling unsaturates which act as inhibitors against hydrolyzation, thereby giving it non-corrosive properties in respect to metals. The benzol referred to is preferably a commercial grade sold under that name and having a boiling range from 150° F.—220° F. with the average being approximately 178° F. and containing small quantities not exceeding about 12% of toluene, xylene, anthracene, naphthalene and hydroquinone and para-amino phenol, which substances appear to materially aid the inhibiting action against hydrolyzation. The same mixture may, therefore, be obtained by using pure benzene and adding small quantities 20 of these substances or any of them. Other unsaturated hydrocarbons such as cracked gasoline cuts having a boiling range between 150° and 225° F. are acceptable. Saturated hydrocarbons 25 of this boiling range such as cracked naphtha may be substituted where small amounts, say up to 3% of toluene, xylene, anthracene, naphthalene 30 or any of them are added.

The non-inflammables may be any of the liquid 35 chlorinated hydrocarbons including carbon tetrachloride, trichlorethylene and perchlorethylene. To this inflammable and non-inflammable mixture I then add a partially chlorinated non-inflammable hydrocarbon such as trichlorethylene or perchlorethylene or tetrachloroethane having 45 a higher boiling point than the average boiling point of the inflammable constituent and also higher than the first mentioned non-inflammable. This latter constituent may be used in comparatively small percentages as a matter of economy.

It will thus be seen that the first described non-inflammable is preferably carbon tetrachloride because it has the lowest boiling point, because its boiling point is closest to the preferred inflammable and because it is the cheapest of the chlo-

50

55

rinated non-inflammable type. This may be used in the range of 60-95% and preferably 65-70% in order to completely eliminate flash and fire with the least volume thereof. The inflammable may be used in the range from 5-39% and the second named chlorinated hydrocarbon may be used from 120% with 3-8% preferred.

In the event that neither hydroquinone nor para-amino phenol are found in the available 10 inflammable hydrocarbon or in case a saturated hydrocarbon such as naphtha is used which is not expected to contain either of these substances, their value as inhibitors against hydrolyzation should be recognized and they or either of them 15 added in amounts up to 1% by volume even though one or more of the other named substances (toluene, xylene, anthracene or naphthalene) is present.

While it is herein stated that saturated inflammables such as naphtha may be used in this solvent, it is preferred that unsaturates only be used as the saturates are chemically inactive, whereas the unsaturates tend to inhibit hydrolyzation by reason of taking up any available 20 hydrogen as is necessary for hydrolyzation. This is important from the standpoint of toxicity because there is a more or less neutralizing action of the unsaturated inflammable with the chlorinated non-inflammable. Also the mixture including unsaturates is non-corrosive, for all practical purposes, on metals to be degreased and on metals employed in the manufacture of dry cleaning and degreasing machinery whereas a corrosive action 25 is definitely noticeable when saturates are used instead. It will thus be seen that, even though a money saving may be made by using naphtha (a saturate) instead of motor benzol (an unsaturate) a product inferior for most purposes results.

40 As an example of preferred formulae for dry cleaning and for certain types of degreasing work the following are given:

Carbontetrachloride	35 parts	35 parts
Benzol	15 do	13 do
Trichlorethylene	2 do	4 do
Hydroquinone or para-amino phenol	0.1%	0.1% by volume

What is claimed is:

1. A solvent comprising benzol boiling within the range 150°-220° F. in amounts from 5-39% by volume, a liquid, non-inflammable chlorinated hydrocarbon having a mean boiling point contained within the boiling range of said benzol in amounts from 60-95% by volume, and a second liquid, non-inflammable chlorinated hydrocarbon having a higher boiling point than that of the first named chlorinated hydrocarbon in amounts 10 from 1-20% by volume.

15 2. A solvent comprising benzol boiling within the range 150°-220° F., a liquid, non-inflammable chlorinated hydrocarbon boiling within the range of said benzol, in amounts from 65-70% by volume, and a second liquid non-inflammable chlorinated hydrocarbon having a mean boiling point higher than that of said benzol and of the first named chlorinated hydrocarbon in amounts 20 from 3-8% by volume, the remainder comprising benzol.

25 3. A solvent comprising benzol boiling within the range 150°-220° F. in amounts from 5-39% by volume, carbon tetrachloride in amounts from 60-95% by volume and trichlorethylene in 25 amounts from 1-20% by volume.

4. A solvent having the following composition by volume:

	Per cent	30
Benzol boiling within the range 150°-220° F.		
F. approximately		25
Carbon tetrachloride		65-70
Trichlorethylene		3-8

5. A solvent having the following composition 35 by volume:

	Parts
Benzol boiling within the range 150-220° F.	15
Carbon tetrachloride	35
Trichlorethylene	2 40

6. A solvent having the following composition by volume:

	Parts
Benzol boiling within the range 150-220° F.	13
Carbon tetrachloride	35 45
Trichlorethylene	4
